(57) **CLAIM**

The ornamental design for a produce pusher, as shown and described.

DESCRIPTION

FIG. 1 is a perspective view of a produce pusher showing our new design;

FIG. 2 is a left side view thereof;

FIG. 3 is a front view thereof;

FIG. 4 is a right side view thereof;

FIG. 5 is a back view thereof;

FIG. 6 is a top view thereof; and,

FIG. 7 is a bottom view thereof.

The broken lines showing of various portions and other elements in the Figures are for the purpose of illustrating unclaimed portions and form no part of the claimed design.

1 Claim, 7 Drawing Sheets
